UNITED STATES PATENT OFFICE.

WILLIAM P. McCORD, OF BEMIS, TENNESSEE.

MAIL-BAG CATCHER AND DELIVERER.

1,409,349.

Specification of Letters Patent. Patented Mar. 14, 1922.

Application filed November 12, 1919. Serial No. 337,466.

To all whom it may concern:

Be it known that I, WILLIAM P. McCORD, a citizen of the United States, residing at Bemis, in the county of Madison and State 5 of Tennessee, have invented certain new and useful Improvements in Mail-Bag Catchers and Deliverers, of which the following is a specification.

This invention relates to a mail transfer 10 apparatus and is designed particularly for use in connection with railway mail service for causing the transfer of mail between a rapidly moving car and a fixed crane at the side of the track.

15 The principal object of the invention is to provide both the mail car and the track crane each with receiving and delivering arms, having devices on the ends thereof of simple construction and positive action for 20 insuring the positive transfer of the mail sacks or bags from one to the other of said devices, the receiving arm of one cooperating with the delivery arm of the other, to insure 25 the transfer of the mail sack in the proper direction.

Another object is to so construct a car carried apparatus that it may be quickly projected and retracted and when retracted 30 will occupy a minimum amount of space and be positioned where it is completely out of the way of the mail clerk.

Another object of the invention is to provide the delivery arm, both of the car apparatus and the track crane with efficient 35 mechanism for holding a mail sack until it is to be delivered and then releasing the same without trouble and danger of being caught or hung on the delivery arm, also to provide receiving devices on the proper 40 arms of the car apparatus and track crane that will catch and hold the mail sacks as they are presented by the delivery arm and prevent all possibility of accidental displacement after they have been received by the 45 proper member.

With the foregoing and other objects in view, which will appear as the description proceeds, the invention resides in the combination and arrangement of parts and in 50 the details of construction hereinafter described and claimed, it being understood that changes in the precise embodiment of the invention herein disclosed may be made within the scope of what is claimed without departing from the spirit of the invention.

In the accompanying drawings:

Figure 1 is a sectional elevation of a portion of a car showing the car carried receiving and delivering apparatus operatively 60 positioned with respect to the receiving and delivering apparatus at the station or at any point along the side of the road bed adjacent the track.

Fig. 2 is a horizontal section through the 65 portion of the car showing a top plan view of the apparatus constituting this invention.

Fig. 3 is an enlarged detail sectional view taken on the line 3—3 of Fig. 1.

Fig. 4 is an end elevation of the car carried mechanism taken on the line 4—4 of Fig. 2, and

Fig. 5 is a transverse section of a portion of the station crane taken on the line 5—5 of Fig. 2.

In the embodiment illustrated a portion 75 of a mail car 1 is shown having a door opening 2 in one side wall and above said opening is mounted the car carried apparatus constituting a part of this invention. This apparatus is secured in position by means of a casting 3 bolted to the side wall of the car above the door opening, a bracket 3^a being arranged in connection therewith to assist in holding the apparatus. Carried by the 80 casting 3 is a sleeve 4 which extends into the car laterally from the side wall thereof and is designed to contain bearing balls 5 located in grooves 7 carried by an arm 6 as is shown clearly in Fig. 3. This arm 6 may be of 85 any suitable or desired length, according to the distance it is designed to project the bag receiving and delivering members.

An elbow shaped lever 8 is pivotally connected at one end with the inner end of the 90 sliding arm 6, as is shown clearly in Fig. 1. The free end of this lever has an operating element in the form of a cord 9 depending therefrom into position convenient to the mail clerk and which is designed for actuating 95 the apparatus in a manner presently to be described. Projecting upwardly from the sleeve 4 is an arm 10, the free end of which extends beyond the rear end of the sleeve and is slotted for passage there 100 through of the inner or pivoted arm of the lever 8. A coiled spring 11 is connected at one end to an upstanding lug 12 carried by the inner end of arm 10 and the other end of said spring is engaged with an eye 13 105 carried by the elbow of lever 8. This spring 11 exerts its tension to normally retract arm

6 and to return it to retracted position after it has been projected by pull exerted on the member 9.

Secured to and depending from the front 5 end of arm 6 is a bar or standard 14 which carries at its lower end laterally projecting arms 15 and 20, the arm 15 being positioned in a plane above the arm 20 and extending in a direction opposite thereto, both of these 10 arms being designed to extend parallel with the car 1 as is shown clearly in Fig. 2. The arm 15 which is the bag delivery member of the car carried apparatus has three longitudinally extending fingers or tines carried 15 thereby and numbered 16, 17 and 18 respectively, the central tine 17 being rectilinear while the other two are offset downwardly at their inner ends as shown at 19 in Fig. 4. This offset portion of the tines 20 16 and 18 is designed to form a seat for the mail bag carrying hoop 22 as is shown clearly in Fig. 4, the central tine 17 being resilient and operating to yieldably hold hoop 22 engaged with its seat.

25 The arm 20 which constitutes the bag receiving member of the car carried apparatus has an inturned hook or bill 21 at its free end positioned on the top thereof as is shown clearly in Figs. 2 and 4 and which is designed to pass through the hoop of the bag to be delivered from the station crane and to hold it engaged therewith after it is delivered.

30 The mail bag carrying hoop 22 is preferably composed of heavy wire and has a loop 23 to receive the mail bag B, the upper end of said loop being curved inwardly and adapted to be engaged by a clamping ring 24 to securely hold said loop closed after 40 the bag has been placed therein, as is shown clearly in Figs. 1 and 2.

A station crane 25 is designed for cooperation with the car carried crane and is shown mounted on a suitable base 26 preferably 45 composed of concrete, although not necessarily so. Rising from this base 26 is a standard 27 having a bearing 28 intermediate of its ends, on which is designed to rest and rotate a substantially inverted U shaped 50 member 29, through the cross bar of which the standard 27 extends, said standard forming a journal for said member. The free ends of the member 29 diverge at a point substantially midway their ends as shown at 55 29^a and are secured to a cross bar 30 mounted to rotate on the upper end of standard 27.

The cross bar 30 has arms 31 hingedly connected therewith and adapted to fold flat thereon when not in use. These hinged 60 members 31 each carries at its terminal a pair of laterally extending spaced fingers 32 which are designed to support the mail bag B to be delivered to the car carried train and another finger 33 extends laterally from the 65 opposite side edge of each member 31 and

is designed as the receiving member of the station crane. A guard 34 is arranged adjacent the inner side of the finger 33 sufficient space being left between its free end and said finger to permit the bag carrying 70 hoop 22 to pass between them and yet will operate to prevent said loop from rebounding off of the finger.

The U shaped cross bar operating member 75 29 has bearings 35 formed in the legs thereof adjacent the inner ends of the diverging portions 29^a. These bearings are designed to receive a locking pin 36 which extends through them and through a registering bearing 37 carried by the standard 27, said 80 pin having a handle 38 to facilitate its insertion and removal. This pin is designed, when positioned in the bearing as shown in Fig. 1, to lock the cross bar against turning; and when it is desired to reverse the 85 cross bar to position it for cooperation with a car carried apparatus on a train coming in the opposite direction, the pin 36 is withdrawn and the member 29 rotated, carrying with it the cross bar 30, and when these 90 parts have been reversed the pin is again inserted and locks them securely against turning.

The bag carrying hoop 39, which is supported by the finger 32 of the station crane 95 95 is similar in construction to the hoop 22, the only difference being that it is mounted differently on the crane, the hoop portion being positioned above the crane and the bag carrying loop 23 below it as is shown 100 clearly in Fig. 5.

In the use of this apparatus the parts being positioned as shown in Figs. 1 and 2, which is the projected position of the car carrying crane, after the train reaches the station 105 the mail clerk in the car 1 releases the member 9 which has been drawn down to project the bag carrying member and the coiled spring 11 operates to retract the arm 6 so that the mail bag carried thereby will 110 be swung into the doorway of the car where it may be conveniently removed by the mail car clerk.

115 It is, of course, to be understood that when a train approaches a station equipped with one of the cranes 25 the mail clerk grasps the member 9 and exerts a downward pull thereon which causes the arm 6 carrying the mail bag to be delivered to shoot outwardly into position and cooperate with the station carried crane and immediately the member 9 is released it is retracted in the manner 120 above set forth.

125 By constructing this apparatus as shown and described it may be used for effectively and reliably receiving and delivering mail for any train, be it fast or slow, without danger of injuring the apparatus or the mail sack.

130 From the foregoing description, taken in

connection with the accompanying drawings, the advantages of the construction and of the method of operation will be readily apparent to those skilled in the art to which 5 the invention appertains and while I have described the principle of operation of the invention together with the device which I now consider to be the best embodiment thereof, I desire to have it understood that 10 the device shown is merely illustrative and that such changes may be made as are within the scope of the claimed invention.

Having thus fully described my invention what I claim as new and desire to secure by 15 Letters Patent is:

1. In a mail bag delivery apparatus, a bar mounted to be projected and retracted laterally of a railway car, a coil spring connected to retract said bar and retain it normally 20 in retracted position, and a lever connected to project the bar against the tension of said spring.
2. In a mail bag delivery apparatus, a bearing carried by a car, a bar mounted to 25 slide in said bearing and to extend laterally from the car when in projected position, delivery and catching arms carried by said

bar, an elbow shaped lever fulcrumed at one end inside said car, a slotted arm carried by said bearing through which 30 the pivoted arm of said lever extends, a coil spring connected with the elbow of said lever, and with said bearing, and means for actuating said lever to project said bar against the tension of said spring. 35

3. In a mail bag delivery apparatus, a sliding bar mounted to be projected and retracted laterally relative to a car, a member depending from the front end of said bar, oppositely projecting delivery and 40 catching arms carried by the lower end of said member, the catching arm having at its free end an inturned hooked member on its upper face and the delivery arm comprising a plurality of longitudinally extending tines, 45 one of which is resilient to clamp a mail bag hoop between them.

In testimony whereof I affix my signature in presence of two witnesses.

WILLIAM P. McCORD.
